UNITED STATES PATENT OFFICE.

FRANK L. O. WADSWORTH, OF PITTSBURG, PENNSYLVANIA, ASSIGNOR TO WINDOW GLASS MACHINE COMPANY, OF PITTSBURG, PENNSYLVANIA, A CORPORATION OF NEW JERSEY.

TAKE-DOWN APPARATUS FOR GLASS CYLINDERS.

No. 890,317.

Specification of Letters Patent.

Patented June 9, 1908.

Application filed May 10, 1906. Serial No. 316,050.

To all whom it may concern:

Be it known that I, FRANK L. O. WADSWORTH, of Pittsburgh, Allegheny county, Pennsylvania, have invented a new and useful Take-Down Apparatus for Glass Cylinders, of which the following is a full, clear, and exact description, reference being had to the accompanying drawings, forming part of this specification, in which—

10 Figure 1 is a side elevation of take-down apparatus embodying my invention; Fig. 2 is a similar view of a portion of the same showing one method of lowering the cylinder on the hoist or other support; Fig. 3 is a plan view of the track and carriage; Fig. 4 is a detail view showing one end of the detachable connection between the hoisting cage and the taking-down carriage; and Fig. 5 is a detail view of a brake-device.

15 My invention relates to the taking-down of glass cylinders which are drawn upwardly from a bath, the object of the invention being to provide an effective apparatus by means of which the cylinder may be rapidly and efficiently handled with a minimum of danger of breakage and without the use of skilled labor.

A further object of the invention is to provide apparatus of this kind which may be operated without danger to the workmen who handle it.

The apparatus embodying my invention provides means by which the cylinder may be engaged in vertical position, and by side-wise movement is swung into position to be lowered upon a suitable horse or support.

The invention also consists in the novel construction, arrangement and combination of parts all substantially as hereinafter described and pointed out in the appended claims.

In the drawings, 2 designates the usual drawing structure, and 3 the hoisting cage which supports the blow-pipe and bait, indicated at 4, by means of which the cylinder is drawn upwardly from the bath.

5 is an inclined track composed of two parallel members which are connected at their upper ends to the drawing structure 2 at the points 6, and whose lower ends are connected to a movable member on the frame, by means of which the points of their support may be varied in the manner herein-

after described. The glass cylinder A is drawn upwardly between the upper portions 55 of these track members in the drawing operation, and is lowered between them in the manner hereinafter described.

7 designates the taking-down carriage which is arranged to travel on the track 5 60 and which consists, in the form shown, of a quadrilateral frame provided with wheels 8 which run upon the track members 5.

9 is a counterbalance connected to the carriage 7 for the purpose of assisting the drawing frame in pulling the carriage upwardly along the track, the counterweight, however, not being sufficiently heavy to fully balance the carriage, it being desirable that the carriage shall have sufficient gravity action to 70 assist its downward movement on the track. Connecting the upper end of the carriage 7 with the hoisting cage 3 is a link 10 which preferably consists of a light tubular member as indicated. Either one or more of these 75 links may be employed as desired. The connection between the upper end of the link or links 10 and the hoisting cage 3 is a detachable one which may conveniently be of the form shown in detail in Fig. 4, in which the 80 upper end of the link is formed with a slot 11 open at one end and engaging a pin 12 of the hoisting carriage. At the upper end of each link there is also journaled a small wheel 13 which is adapted to one of the track members 85 5 for the purpose which will presently appear.

14 designates the cylinder grips. These grips may be of any suitable form, being carried by the frame 15 which is suspended by a 90 link connection 16 from a transverse shaft or support 17 which is carried by the free end portions of the horizontal arms or levers 18 which are secured on a transverse shaft 19 journaled in the carriage 7 near its lower end. 95 The shaft 19 has a depending arm 20 one end of which carries a detachable weight 21. Depending from the longitudinal members of the frame of the carriage 7 are two sectors 22, the teeth of which are engaged by pawls 23 100 on a cross shaft 24 carried by the lever arms 18 and actuated by a hand lever 25 through the bell crank and connections 26, as shown in Fig. 1.

27 designates a brake-shoe which is interposed between a disk 28 on the transverse

support 17 and a smaller disk 29 on the pin 30 which forms the connection between the grip frame 15 and the suspension link 16, the purpose of this brake being to prevent undue 5 swinging movement of the cylinder in case it should become detached from the blow pipe in the operation of lowering, as sometimes occurs.

The track member 5 may consist of rigid 10 bars or rails of any suitable character pivotally connected at their upper ends to the drawing structure 2, and so connected at their lower ends that their points of support may be raised or lowered as before indicated. 15 I prefer, however, that they shall be of flexible character, so that not only may their points of support be changed, but that they may be flexed or bent in a manner to facilitate the lowering of the cylinder onto the 20 horse or other support in the manner to be described. Various means may be provided for shifting the point of support of these track members. In the drawing, I have shown them as connected to levers 31 which 25 are secured to a connecting shaft 32 mounted in supports 33. The levers 31 are provided with the counterweights 34, the levers being held in position to maintain the tension of the track members when loaded, by means 30 of a brace 35 which is connected to a lever arm 36 depending from the shaft 32. The connection of the track members 5 to the lever arms 31 is preferably made by means of turn-buckles 37 which provide convenient 35 means for adjusting their tension.

A glass cylinder having been drawn upwardly from a bath in the usual manner in the position shown in full lines in Fig. 1, the the operation of lowering such cylinder is as 40 follows. The grips 14 are engaged with the cylinder as indicated in Fig. 1, and the hoisting cage is then lowered on its guides, thereby lowering the cylinder A, and through the link connections 10 moving the carriage 7 downwardly on the track 5, this movement of the carriage causing the cylinder to be gradually swung until it reaches the dotted position X, in Fig. 1. When this position is reached, the wheels 13 at the upper ends of the links 10 45 are in engagement with the upper ends of the tracks 5, which prevents further downward movement of the links, and the continued descent of the cage 3 effects its disconnection from these links, the pins 12 readily disengaging themselves from the slots 11 before 50 described. Further descent of the hoisting cage causes the blow pipe connection to move from the point x to the point y, and the cylinder now assumes the dotted position 55 Y. When this position is reached the grip frame 15 engages the transverse shaft or support 19 of the carriage 7 which prevents further downward movement of the blowpipe and of the cylinder, and causes the blow-

pipe connection to be automatically disengaged from its connection with the cage 3. The cylinder is now supported entirely by the carriage 7 which is moved on the tracks 5 to the desired position over the horse or other support onto which the cylinder is to 70 be lowered, the descent being effected by gravity. Too rapid descent is prevented by the action of the counterweight 9 and also by the operator who has hold of the lever arm 20 and walks with the carriage as it moves 75 downwardly on the track. The lowering of the cylinder onto the horse or other support may be effected in a number of ways, two of which are shown in the drawing.

In the method illustrated by Fig. 1, the 80 pawls 23 are released by the operator from their engagement with the toothed sectors 22, and the levers 18 and 20 are moved into the position shown in dotted lines. The cylinder having been thus lowered onto the 85 horse, the operator releases the grips 14 by means of the lever 14^a, and these are automatically moved away from the cylinder by the action of the counterweight 21. The operator now moves the carriage upwardly 90 on the track until it is in the dotted position X of Fig. 1, which may be easily done owing to the action of the counterweight 9. When the position X is reached the hooks 11 of the links 10 are in position to be engaged by the 95 pins 12 of the drawing cage as the latter moves upwardly in drawing a new cylinder, and the carriage is moved back to its original position at the upper portion of the tracks 5 by the ascent of the cage.

In the method of lowering the cylinder shown in Fig. 2, the levers 31 are moved into the position shown in full lines in said figure, thereby lowering the points of support of the lower ends of the tracks 5 and causing them 105 to slack. The center of gravity of the cylinder A being substantially below the upper wheels 8 of the carriage 7 causes the tracks to flex at this point and to assume the position shown, thereby permitting the cylinder 110 to be lowered onto the hoist without moving the levers 18. Either one of these methods of lowering may be used as may be most convenient in any particular case. The method last described and illustrated in Fig. 2 is of 115 particular value when the cylinder has not been drawn to its full length, since the track members 5 may flex to such an extent as to permit the cylinder to be lowered onto the horse at any desired point. The method shown in Fig. 1 requires the carriage to be moved a certain distance down the track before the cylinder can be lowered, the extent of lowering movement effected by the levers 18 being limited.

The advantages of my invention will be apparent to those skilled in the art. The use of flexible track members for the taking-

100

115

120

125

down carriage provides a track which can be quickly and inexpensively erected and dismantled, and transferred from one point to another for temporary use.

5 The operations are simple and easily controlled, and breakage of the glass and danger to the operators are greatly lessened.

A further advantage consists in automatically effecting the disconnection between 10 the hoisting cage and the take-down carriage at the proper time, the operation being effected by simple mechanical means, and without the necessity for electro-magnetically operating disconnecting devices. Also 15 in the automatic disconnection of the blow-pipe connection as described.

Still another advantage consists in the fact that the taking-down carriage is operated without the use of independent motors, 20 its movement on the track being effected, so far as any motive power is required, by the motor which operates the hoisting cage.

Another and important advantage of the 25 invention consists in the use of flexible track members, which render the movement of the carriage much simpler and easier than is possible with a rigid track, and avoids shocks by reason of the degree of elasticity which is thus provided.

30 Many variations may be made in the form and in the details of construction and arrangement of the various parts without departing from my invention.

I claim:

35 1. In a take-down device for glass cylinders a drawing device, an inclined double track between the members of which the cylinder is drawn and lowered, and a carriage movable on the track and having grips for 40 the cylinder; substantially as described.

2. In a take-down device for glass cylinders, an inclined double track between the members of which the cylinder is drawn and lowered, a drawing device a carriage movable along the track, and having grippers for 45 the cylinder, and a connection between the carriage and the drawing device; substantially as described.

3. In a take-down device for glass cylinders, an inclined track, a drawing device a carriage movable on the track and having grips for the cylinder, a connection between 50 the carriage and the drawing device, and means for automatically disengaging such connection; substantially as described.

4. In a take-down device for glass cylinders, an inclined track, a drawing device a carriage movable on the track and having grips for the cylinder, a connection between 55 the carriage and the drawing device, and means for automatically-engaging and disengaging such connection at predetermined points in the movement of the cage; substantially as described.

5. In a take-down device for glass cylinders, a drawing device supporting a blow-pipe connection or bait, a take-down device having grips for the cylinder, and means for checking the movement of the cylinder relative to the taking-down device to thereby 65 effect the disconnection of the blow-pipe connection or bait from the drawing device at a predetermined point in its downward movement; substantially as described.

6. In a take-down device for glass cylinders a drawing device, an inclined track, a take-down device movable on the track, and means for changing the point of support of 70 one end of said track; substantially as described.

7. In a take-down device for glass cylinders a drawing device, an inclined track, a take-down device movable on said track, and means for changing the point of support of 75 one end of the track and thereby changing the inclination of said track; substantially as described.

8. In a take-down device for glass cylinders a drawing device, an inclined track, a take-down carriage movable on the track, 80 and means for raising and lowering the point of support of the lower end of the track; substantially as described.

9. In a take-down device for glass cylinders a drawing device, an inclined track 85 adjacent to the drawing device composed of flexible members held under tension; substantially as described.

10. In a take-down device for glass cylinders a drawing device, an inclined track 90 adjacent to the drawing device composed of flexible members under tension, and means for changing the point of support of the said members at one end; substantially as described.

11. In a take-down device for glass cylinders a drawing device, an inclined track adjacent to the drawing device composed of one or more flexible members, and means for holding said members under tension; substantially as described.

12. In a take-down device for glass cylinders a drawing device, an inclined track adjacent to the drawing device composed of one or more flexible members, and a lever 115 device to which the member or members are connected at their lower ends; substantially as described.

13. In a take-down device for glass cylinders a drawing device, an inclined track 120 adjacent to the drawing device composed of one or more flexible members, and a counter-weighted lever device to which the member or members are connected at their lower ends; substantially as described.

14. In a take-down device for glass cylinders a drawing device, a flexible track, means for normally holding said track under

tension, means for releasing the tension, and means for automatically restoring the tension; substantially as described.

15. In a take-down device for glass cylinders a drawing device, a track, a carriage movable thereon, and a rigid lever system carried by the carriage and having grips for the cylinder; substantially as described.

16. In a take-down device for glass cylinders a drawing device, a track, a carriage movable on the track, a rigid lever system carried by the carriage and having grips for the cylinder, and means for changing the angular position of the lever system with respect to the carriage; substantially as described.

17. In a take-down device for glass cylinders a drawing device, a track, a carriage movable on the track, a rigid lever device mounted on the carriage and having grips for the cylinder, means for changing the angular position of the lever device with reference to the carriage, and means for holding said device in a definite position with respect to the carriage during a portion of the movement of the latter; substantially as described.

18. In a take-down device for glass cylinders a drawing device, an inclined track, a carriage movable on the track, a rigid lever device mounted on the carriage, a grip frame suspended from the lever device, and means for changing the angular position of the lever device with respect to the carriage; substantially as described.

19. In a take-down device for glass cylinders a drawing device, a track, a carriage movable along the track, and a rigid counter-

weighted lever device mounted on the carriage, and having grips for the cylinder; substantially as described.

20. In a take-down device for glass cylinders a drawing device, a track, a carriage movable thereon, a lever device mounted on the carriage, grips for the cylinder, and suspending links connecting the grips with the lever device; substantially as described.

21. In a take-down device for glass cylinders a drawing device, an inclined track, a carriage movable on the track, a rigid lever system mounted on the carriage, grips for the cylinder suspended from the lever system, and a brake device in connection with such suspension; substantially as described.

22. In a take-down device for glass cylinders, an inclined track, a drawing device, a carriage movable on the track, and links connecting the carriage with the drawing device, said links having a detachable connection with the drawing device and also adapted to move on the tracks; substantially as described.

23. The combination with vertical glass drawing apparatus having a drawing device, and means for raising and lowering the same, of a coöperative take-down comprising a cable extending between two fixed points, and a gripping device mounted upon and movable along said cable.

In testimony whereof, I have hereunto set my hand.

F. L. O. WADSWORTH.
